UNITED STATES PATENT OFFICE.

PHILIP MUELLER, LUCIEN W. MUELLER, AND WILLIAM J. MIX, OF DECATUR, ILLINOIS, ASSIGNORS TO ADOLPH MUELLER, TRUSTEE, OF DECATUR, ILLINOIS.

ATTACHMENT FOR LAVATORY-OUTLET-VALVE DEVICES.

Application filed October 24, 1925. Serial No. 64,571.

The present invention relates to improvements in attachments for lavatory outlet valve devices of the type which is actuated by reciprocating a push rod that is in turn connected with means for opening and closing a lavatory waste valve.

It is customary to provide such valve actuating push rods with enlarged heads or handles and as commonly constructed, the base of such heads or handles contacts with the outer end of the cap or escutcheon which is commonly provided about the push rod at the outer end of the guide or passage in the stationary member of the fixture or wall through which the rod reciprocates. As such escutcheons are commonly made from vitreous material, it frequently happens that the repeated striking of the handle or knob at the outer end of the valve actuating push rod causes fracture of such escutcheon.

The object of the present invention is to provide means by which the reciprocating movement of the valve actuating push rod toward the escutcheon will be positively limited so that the knob or handle at the outer end of the rod will not be permitted to strike the escutcheon.

The invention is applicable to valve actuating means of various types but in the accompanying drawing is shown in connection with a particular means which constitutes the subject of a companion application.

In the drawings:

Figure 1 is a vertical sectional view through a lavatory waste valve actuating means embodying the invention.

Figure 2 is a detail.

The particular type of valve illustrated is that commonly known as a "pop-up drain" and includes a tubular valve having an enlarged head 1 which is adapted to be seated in a properly shaped valve seat 2 provided in the bottom of the lavatory basin 3. The tubular valve is provided with lateral openings or ports 4 through which the waste water from the basin will flow when the valve is lifted to raise the head 1 from the seat 2 and when the valve head is seated on the seat 2 or in closed position, said ports 4 cooperate with a channel formed in the body of the basin and communicating with an overflow opening 5 therein.

Reciprocation of the valve is effected by a lever 7 which is fulcrumed within a suitable housing projecting laterally from the main

valve fitting and has its inner end suitably connected with the valve so that as the lever is rocked about its fulcrum, the valve will be reciprocated to or from the seat 2. The lever 7 is connected with a push rod shown as being of such form that the length thereof may be varied to accommodate it to basins of different depths, although it will be evident that a single or one-piece push rod may be employed as the details of this do not constitute a novel feature of the present invention.

The push rod 8 extends upward through a guide 9 which is adapted to be secured to a portion of the basin or to any other relatively stationary support. As shown, this guide comprises a sleeve-like body 9 having an exterior thread formed thereon and provided at its outer end with an annular flange 10. The flange 10 is adapted to contact and overhang the outer face of the support 11 to which the guide is secured and preferably a suitable washer 12 is arranged between such surface and the flange.

An escutcheon 13, preferably made of vitreous material, is positioned about the outer end of the guide and, as shown, is held in position by an annular flange on a sleeve 14 which is threaded into the guide and bears against the outer end of the escutcheon.

The lever actuating rod 8 extends through the guide and on the outer end thereof is secured a knob or handle 15.

Closely fitted to the rod 8 is a sleeve 16 which extends into the guide 9 and the inner end of which is adapted to contact with a cooperating inwardly projecting stop on the guide before the knob or handle 15 can strike the escutcheon retaining sleeve 14 as the rod is moved downward or inward through the guide to lift the valve 1. The stop member on the guide 9 which cooperates with the inner end of the sleeve 16 may be formed in any suitable manner. As shown, the inner end of the guide has an opening through which the push rod 8 extends which is of slightly less diameter than the interior bore of the body of the guide so that an annular shoulder is provided about the push rod and with this shoulder the inner end of the sleeve 16 contacts to limit inward or downward movement of the push rod.

From the drawing it will be seen that when the push rod has been depressed to the

limit of its possible movement, the knob or handle, as represented in the dotted lines, will be some distance above the flange of the escutcheon retaining member 14.

5 To cushion the force of the shock produced by contact of the lower end of the sleeve 16 with the interior shoulder on the guide 9, which force is transmitted through said guide and escutcheon retaining member to 10 the vitreous escutcheon, and effectually guard against fracturing the escutcheon we provide suitable pressure absorbing means above and below the escutcheon.

As illustrated a flexible, for example rubber, gasket 30 is interposed between the upper end of the escutcheon 13 and the flange on the retaining member 14. A similar gasket, 31, is interposed between the lower face of the escutcheon and the metal washer 12; and as shown this is supplemented by a smaller flexible washer, 32.

The yielding gaskets referred to effectually protect the escutcheon from damage resulting from violent depression of the knob or handle 15.

As a precaution against the possibility of clamping the escutcheon too tightly the periphery of the flange on the securing member 14 is preferably smooth, having no corrugations or special means for being gripped. In other words, the tightening of the member 14 is effected only by the plumber's fingers.

The guide 9 may be attached to the support 11 by any suitable means. As shown, a washer 20 surrounds the threaded stem or body of the guide and through this washer extend a plurality of set screws 21, which are adapted to be turned into close engagement with the inner surface of the support. A nut 22 engaging the thread on the guide 9 bears against the washer 20 and the guide is thus firmly secured to the support 11.

It will be seen that when the parts are properly adjusted the ends of the washer 20, which as shown in Figure 2 is preferably of substantially elliptical form, are deflected downward from the points of contact with the nut 22.

50 The washer 20 need not necessarily be of resilient metal, cast brass having been satisfactorily employed. In assembling the parts the nut 22 is to be screwed up until the washer begins to bend, and thereafter the screws 21 are set up until the head of each is practically flush with the outer edge of the washer.

From the foregoing description and the drawing, it will be seen that the invention 60 provides a very simple but effective means for preventing the escutcheon 13 from being injured by blows delivered by the knob or handle at the outer end of the valve operating rod.

65 There can, of course, be considerable va-

riation of the details illustrated without departing from the invention, and it will be evident that the invention is not limited to use with the exact form of valve or operating lever means illustrated.

Having thus described our invention, what is claimed is:

1. The combination with the operating push rod of a lavatory outlet valve having a knob or handle at its outer end, of a guide for said rod adapted to be attached to a suitable support, and having an annular flange about its outer end, an escutcheon surrounding the rod and extending over the flange at the outer end of the guide, means engaging the guide and escutcheon for holding the latter in position, and means for limiting movement of the rod through the guide to prevent contact of the knob or handle thereon with the escutcheon.

2. The combination with the operating push rod of a lavatory outlet valve having a knob or handle at its outer end, of a guide for said rod adapted to be attached to a suitable support, and having an interior thread adjacent its outer end and an annular flange at said outer end, an escutcheon surrounding the rod and extending over the flange at the outer end of the guide, a sleeve having a threaded body engaging the interior thread of the guide and a flange overlying the outer end of the escutcheon, and means for limiting movement of the rod through the guide to prevent contact of the knob or handle thereon with the escutcheon.

3. The combination with the operating push rod of a lavatory outlet valve having a knob or handle at its outer end, of a guide for said rod adapted to be attached to a suitable support, and having at the outer end a lateral projection adapted to contact with the outer face of the support to which the guide is attached, means connected with the guide for engaging the inner face of said support, an escutcheon surrounding the rod adjacent the outer face of said support, and means for limiting movement of the rod through the guide to prevent contact of the knob or handle thereon with the escutcheon.

4. The combination with the operating push rod of a lavatory outlet valve, of a guide for said rod adapted to extend through a passage in a suitable support and having at its outer end means for engaging said support, the body of said guide being provided with an exterior thread, a washer surrounding the threaded section of the guide, a plurality of set screws extending through said washer and adapted to be engaged with the support through which the guide extends, and a nut engaging the thread on the guide and bearing against the said washer for holding it in contact with said support.

5. The combination with the operating push rod of a lavatory outlet valve, of a

- guide for said rod adapted to extend through a passage in a suitable support and having at its outer end means for engaging said support, the body of said guide being provided
- 5 with an exterior thread, a washer surrounding the threaded section of the guide, a plurality of set screws extending through said washer and adapted to be engaged with the support through which the guide extends, a
- 10 nut engaging the thread on the guide and bearing against the said washer for holding it in contact with said support, an escutcheon surrounding the rod adjacent the outer face of said support, a knob or handle af-
- 15 fixed to the outer end of the push rod, and cooperating stop means on the rod and guide for limiting movement of the rod through the guide in one direction and preventing contact of the knob or handle with
- 20 the escutcheon.
6. The combination with the operating push rod of a lavatory outlet valve having a knob or handle at its outer end, of a guide for said rod adapted to be attached to a
- 25 suitable support, a sleeve secured to the rod and extending into the outer end of the guide, and means within the guide adapted to cooperate with the inner end of said sleeve to limit movement of the rod through
- 30 the guide in one direction and prevent contact of the handle or knob with the escutcheon.
7. The combination with a lavatory waste valve and actuating means therefor includ-
- 35 ing a push rod having a knob or handle at its outer end, of an escutcheon surrounding the rod adjacent its outer end, means for preventing the knob or handle of the push rod from striking the escutcheon when the
- 40 rod is moved in a direction to carry the knob or handle toward the escutcheon, and means for cushioning the blow produced by such movement of the rod.
8. The combination with a lavatory waste
- 45 valve and actuating means therefor includ-
- ing a push rod having a knob or handle at its outer end, of a guide for said rod adapted
- to be attached to a suitable support, an es-
cutcheon surrounding the rod beyond the end
of the guide adjacent said knob or handle, a
resilient gasket surrounding the rod and
bearing upon the adjacent end of the es-
cutcheon, means attached to the guide and
bearing upon said gasket, and cooperating
stop means on the rod and guide for limit-
ing movement of the rod to prevent contact
between the knob and escutcheon, substan-
tially as described.
9. The combination with a lavatory waste valve and actuating means therefor includ-
ing a push rod having a knob or handle at its outer end, of a guide for said rod adapted
to be attached to a suitable support, and
provided at its end adjacent the knob or han-
dle with an annular flange, an escutcheon
surrounding the rod between said flange and
the said support, resilient gaskets surround-
ing the rod between the escutcheon and said
flange and support, respectively, and cooper-
ating stop means on the rod and guide for
limiting movement of the rod to prevent con-
tact between the knob and escutcheon, sub-
stantially as described.
10. The combination with a lavatory waste valve and actuating means therefor includ-
ing a push rod having a knob or handle at its outer end, of a guide for said rod adapted
to be attached to a suitable support, and pro-
vided at and adjacent its end nearest the
knob or handle with spaced annular flanges,
an escutcheon surrounding the rod between
said flanges on the guide, resilient gaskets
interposed between both of said flanges and
the escutcheon, and cooperating stop means
on the rod and guide for limiting movement
of the rod to prevent contact between the
knob and escutcheon, substantially as de-
scribed.

In testimony whereof we have hereunto set
our hands.
